2,379,590

VAPOR SEPARATOR

Wilbur C. Oliver, Los Angeles, Calif., assignor to
George M. Holley and Earl Holley

Application March 7, 1944, Serial No. 525,395

2 Claims. (Cl. 261—72)

The object of this invention is to separate the vapor in an airplane carburetor generally and specifically in those of the low pressure (suction) type. The fuel is volatile even at sea level so that at normal levels with normal air pressures (10'-30' of Hg) the fuel is excessively volatile. Unless the fuel is maintained under a pressure of, say 15 lbs. per square inch, trouble is to be expected. Hence, the problem of vapor separation is much more difficult in a carburetor of the low pressure (suction) type than with the ordinary pressure type which has come into general use during the last four years. However, even with the pressure type carburetor vapor separation is of considerable importance so that this invention is not limited to any particular type of carburetor.

The drawing shows diagrammatically the elements of my invention.

Fuel enters at 10 and flows past the valve 11 controlled by a lever 12 which is connected to the diaphragm 15. The corresponding lever 14 is connected to the corresponding diaphragm 13. These details of the fuel chamber control means are no part of this invention. The fuel in the fuel chamber 16 is thus maintained at a constant level.

A vapor separating chamber 17 is a part of chamber 16. A fuel passage 19 obtains its fuel from chamber 16 through port 18. A float 20 is guided on a hollow pin 21 which is provided with ports 22 which, when the float 20 is in the position shown, are uncovered. A passage 23 is thus, under such circumstances, put in communication with the upper part of the chamber 17. This passage 23 communicates with the high vacuum existing in a chamber 24 which is located in back of a throttle 25, which throttle forms a variable venturi; see below. The chamber 24 communicates through an opening 26 with the throat of the variable venturi formed by the throttle 25 and a similar throttle 27.

The throttle 25 engages with the corresponding throttle 27 by means of two gears 28 and 29. The gear 28 engages with the gear 30 mounted on the shaft 31 which carries the cam 32. The result is that when the throttles 25 and 27 are opened, the cam 32 is rotated and the lever 33 is moved to the left, carrying with it the needle 34 which controls the fuel flow in the passage 19 so that more fuel flows down the passage 35. The elements whereby the throttles 25 and 27 open and the needle 34 opens admitting fuel are not a part of this invention, being a part of a

well-known airplane carburetor of the low pressure type (M. E. Chandler, Reg. No. 22,254), which has come into general use during the last seven years.

5 A passage 36 communicates with the back side of the throttle 25 and is therefore subjected to the suction of the venturi through the opening 26. Passage 36 is controlled by a valve 37 mounted on a diaphragm 38. The diaphragm forms 10 the left-hand side of an air chamber 39. This air chamber 39 communicates through passages 41 and 23 with the carburetor inlet air pressure. The passage 23, however, has a restricted communication with the carburetor inlet air pressure through restriction 42 and therefore will not materially diminish the suction existing in passage 23 or chamber 39 if said suction is insufficient to close valve 37 against the tension of spring 40. If said suction is sufficient to close valve 37 against the tension of spring 40, restriction 42 allows air to flow into passage 23 and chamber 39, returning valve 39 to a balanced position such that a constant differential pressure is automatically maintained across 15 diaphragm 38 and hence ports 22, whether or not vapor is being removed through ports 22. This constant differential pressure is governed by the tension of spring 40.

30 Operation

When vapor accumulates in chamber 16, and therefore chamber 17, the vapor displaces fuel and the fuel level decreases, resulting in the lowering of the buoyant float 20 and the uncovering of ports 22. The vapor is therefore removed through ports 22 by means of the suction created by the airflow past the throttles 25 and 27 via ports 26, chamber 24, passages 36 and 23. Valve 27 remains open provided the differential 35 pressure across the diaphragm 38 is insufficient to produce a force large enough to overcome the tension of spring 40 and close the valve 37. The restriction 42 is small compared to the ports 26, chamber 24, and passages 23 and 36, and therefore will not materially diminish the vapor separator pressure differential across ports 22.

If the pressure differential across diaphragm 38 is sufficient to close valve 37 because of a lower pressure at port 26, the small amount of air flowing through restriction 42, passages 23 and 41 into chamber 39 will reduce the differential pressure across diaphragm 38 and cause valve 37 to assume a balanced, or "lap" position which will therefore automatically regulate a constant pressure differential across diaphragm

38 and hence ports 22. This constant pressure differential is governed by the tension of spring 40 at the balanced position of valve 37. Valve 37 will naturally have a greater opening when vapor is being removed through ports 22, but the differential will remain the same.

Restriction 42 need only be large enough to accommodate the leakage of valve 37 in a closed position in order to break the suction which would be created in passage 23 if the ports 22 were closed and no restricted line 42 provided.

What I claim is:

1. A vapor separator for use in combination with an airplane carburetor having a throttle controlling the flow of air therethrough, comprising a vapor separating chamber, a float therein, a vapor outlet therefrom constructed and arranged so as to be uncovered by said float when the fuel level in said chamber falls below a predetermined level, a first passage connect-

ing said outlet to the air entrance to said carburetor a restriction in said passage, a second passage connecting said outlet to the engine side of said throttle, a valve in said second passage, 5 a moving wall subjected on one side to the pressure in the second passage and on the other to the pressure in said vapor separating chamber and to the force exerted by a spring, said valve being operatively connected to said moving wall 10 whereby the depression applied to the vapor outlet is prevented from becoming excessive.

2. A device as set forth in claim 1 in which the carburetor fuel supply is supplied to a pressure reducing chamber formed by a second moving wall which regulates the level of the fuel 15 in said vapor separating chamber and in which this pressure reducing chamber is in free communication with the vapor separating chamber.

WILBUR C. OLIVER.
